VALVE MECHANISM FOR HYDRAULIC MOTORS

Augustus M. Sanborn, Porterville, Calif.

Application October 16, 1936, Serial No. 105,971

5 Claims. (Cl. 121—159)

This invention relates to a valve mechanism for a hydraulic motor and particularly to a motor of the reciprocating type which is provided as a unitary part of a portable water driven spray pump such as shown for instance in my Patent Number 1,831,035 dated November 10, 1931.

The principal object of my present invention is to provide a valve mechanism for the purpose which is an improvement over existing devices of this character, in that it is extremely simple and inexpensive in construction, not only as regards the structure and operation of the movable valve unit itself, but also with respect to the cylinder and valve housing casting, as will be apparent from the description to follow.

In the drawings similar characters of reference indicate corresponding parts in the several views:

Figure 1 is a vertical section of the motor and valve structure showing the position of the parts when the motor piston is moving up.

Figure 2 is a vertical section of the valve structure on the line 2—2 of Fig. 1.

Figure 3 is a cross section on the line 3—3 of Fig. 1 and Figure 4 is a cross section on the line 4—4 of Fig. 1; the parts in the various sections being all in the same position.

Figure 5 is a view similar to Fig. 1 but showing the position of the parts when the piston is moving down.

Figure 6 is a vertical section of the valve structure on the line 6—6 of Fig. 5.

Figure 7 is a cross section on the line 7—7 of Fig. 5 and Figure 8 is a cross section on the line 8—8 of Fig. 5; the parts in these sections also being all in the same position.

Figure 9 is a fragmentary section on the line 9—9 of Fig. 5 showing the valve rotating units.

Referring now more particularly to the characters of reference on the drawings, 1 denotes the power or motor cylinder and 2 indicates the pump cylinder; these cylinders being disposed in spaced alignment and rigidly connected by suitable means.

45 The piston 3 of the power cylinder is connected to that and the pump cylinder by a common piston rod 4 which is exposed between the cylinders. The construction of the pump itself, which is of course of the reciprocating type, does not form any part of the present invention and I have therefore deemed it unnecessary to specifically show or describe the same.

Formed with the cylinder 1 to one side of and parallel to the same is a valve housing forming 55 cylindrical valve chamber 5 which is closed at its

upper end by a common plug 6 and at its lower end by a backing gland plug 7. Slidably and turnably mounted in the valve chamber is a piston valve comprising a central hollow stem 8 closed at its ends, top and bottom pistons 9 and 10 respectively which are longer than the stroke of the valve and intermediate relatively narrow pistons 11; all said pistons engage the wall of the valve chamber with a running fit.

The stem is provided with a port 12 between the pistons 11 to provide communication between the interior of the stem and the adjacent portion of the valve chamber. A passage 13 leads from the interior of the stem to the periphery of the piston 9 adjacent the top while a passage 14 leads from the interior of the stem to the periphery of the piston 10 adjacent the bottom; these passages being set at an angle of 45° to each other.

The pistons 9 and 10 from their adjacent ends are hollowed out about the stem to communicate with the portions of the valve chamber between said pistons and the adjacent piston 11; the piston 9 having a port 15 leading through its wall adjacent the top and the piston 10 having a port 16 leading through its wall adjacent the bottom. The ports 15 and 16 are set at an angle of 135° to the corresponding passages 13 and 14 and so that they are spaced 45° apart relative to each other. Diametrically opposed longitudinal channels 17 and 18 are cut in the wall of the valve chamber at the top to alternately register with the passage 13 and port 15 respectively; while similar channels 19 and 20 are cut in the wall of the valve chamber at the bottom to alternately register with the passage 14 and port 16 respectively. The length of these channels relative to the stroke of the valve (which is limited by the top and bottom plugs) is such that said channels are always closed against direct communication with the valve chamber between the pistons.

A branched intake passage 21 formed in the valve housing communicates with the chamber 5 both above and below the intermediate pistons 11 but never between the same; an exhaust passage 22 in the housing being always in communication with the valve chamber between the intermediate pistons. A passage 23 leads from the top of the cylinder 1 to the valve chamber 5 above the exhaust passage while a passage 24 leads from the bottom of the cylinder to the valve chamber below the exhaust passage. The chamber ends of these passages are so disposed that when the piston valve is at the top of its stroke the upper passage 23 is in communication with the exhaust passage while the passage 24 is then in commun- 55

cation with the intake passage 21 below the lower piston 10, and vice versa.

The valve is moved axially in one direction or the other by water pressure and such movement is controlled by the rotation of the valves through 45° in one direction or the other as will now be seen. Such rotative movement is mechanically imparted to the valve in the following manner:

The stem of the valve terminates in a non-circular extension 25 depending from the piston 10, which extension slidably but non-turnably engages a socket formed in a sleeve 26 turnably mounted against axial movement in the backing plug 7. This sleeve has a stem 27 depending into the clear below plug 7, on which is fixed a hub 28 having opposed spiral flanges 29 disposed with a relatively large pitch and having a total extent of 45°. Mounted in connection with the pump and power cylinders in an exposed position between and parallel to the piston rod and valve is a rod 30. A yoke Y which includes vertically spaced bosses 31 slidable on the rod 30, is provided on one side with a projecting plate 32. This is formed with a bore 33 to surround the hub 28 and with opposed spirally cut slots 34 through which the flanges 29 closely project (see Fig. 9). A forked arm 35 is secured on the rod 4 and engages a collar 36 secured on the rod 30 between the bosses 31.

In operation, when the piston 3 has descended to the bottom of its stroke the collar 36 has engaged the lower boss 31 and has moved the yoke down, moving the plate 32 down on the hub 28. Such movement of the plate of course rotates the hub and the valve to which it is operatively connected through an arc of 45° by reason of the spiral flanges 29 which are engaged by the plate slots 34. When the valve is thus rotated, it is initially at the bottom of its stroke but in the rotative position shown in Figs. 1 to 4. In other words, the passage 13 of the upper piston 9 is in register with the channel 17 while the port 15 is closed as shown in Fig. 3; while the passage 14 of the lower piston 10 is closed and the port 16 is in register with the channel 20 as shown in Fig. 4.

Water from the intake 21 then enters the valve chamber below the piston 10 through the port 16 and channel 20 (see Fig. 2) forcing the valve up. At the same time water previously admitted to the valve chamber above the upper piston 9 is discharged through channel 17, passage 13 and the interior of the valve stem to the port 12 and turns to the exhaust passage 22. When the valve is in its upper position, the lower branch of the intake 21 is in communication with the passage 24 while the upper passage 23 is in communication with the exhaust. Water thus passes under the piston 3 and moves the same on its upstroke.

When the piston is about at the top of its stroke the collar 36 engages and raises the yoke Y causing the member 28 and the valve to be rotated 45° in the opposite direction, or to the rotated position shown in Figs. 5 to 8. In this position, the passage 13 of the upper piston 9 is closed while the port 15 is in register with the channel 18. Also the passage 14 of the lower piston 10 then registers with the channel 19 while the port 16 is closed. Water from the intake 21 can thus enter the valve chamber above the piston 9 forcing the same down while the water below the piston 10 will be discharged. The various channels are at least as long as the full stroke of the valve so that there is no interference with the proper flow of the valve controlling water

through the full stroke of the valve. With the reversed or lowered position of the valve, the upper passage 23 is now in communication with the intake passage 21 while the lower passage 24 is in communication with the exhaust passage 22 as shown in Fig. 5.

It will be seen that the arrangement of ports and passages allows me to reverse the flow of water if desired, or in other words, to use the passage 22 as the inlet and the passage 21 as the exhaust. This might be of advantage in balancing the thrust or end pressure on the valve and the upward pressure needed in actuating the valve rotating device and thus lessen somewhat the effect of the frictional resistance incident to such rotation of the valve. This is because, with such a reversal of flow of the water, the valve would be in its lower position when the pump is on its upstroke, and vice versa.

It is here to be noted that while I have initially intended this valve mechanism for use in connection with a portable spray pump, said mechanism may be used in connection with any form of reciprocating hydraulically operated lifting pump.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In a fluid motor having a cylinder and a piston slidable therein, a closed-end valve chamber parallel to the cylinder, a valve slidable in the chamber and including a stem, and spaced intermediate pistons, said valve being turnable in the chamber and being slidable through a stroke of fixed length, a branched intake passage connecting with the chamber at spaced points always beyond the valve pistons, an exhaust passage connecting with the valve chamber at a point always between said pistons, cylinder passages leading from the cylinder at its ends to longitudinally spaced connections with said chamber in such relation to the valve pistons and said other passages as to alternately establish communication with the intake and exhaust passages with the movement of the valve through its stroke, fluid actuated means to move the valve through said stroke operable upon rotation of the valve a predetermined arcuate amount, and means controlled by movement of the cylinder piston to adjacent either end of its stroke to thus rotate the valve.

2. A structure as in claim 1, in which said fluid actuated means comprises end pistons on the valve stem; said stem, end pistons and the walls of the chamber engaging the same being formed with passages to allow of a flow of water from the intake passage to the chamber at the head of one end piston while water may pass to the exhaust passage from the chamber at the head of the other end piston.

3. A structure as in claim 1, in which said fluid actuated means comprises end pistons on the valve stem, the latter being hollow but closed at its ends and having a port communicating with the valve chamber between the intermediate pistons, the end pistons having passages

leading to the periphery thereof from the interior of the stem and other circumferentially spaced passage means to the periphery of said pistons from the valve chamber between the end and intermediate pistons; there being circumferentially spaced channels in the walls of said valve chamber to register with said passages and passage means throughout the stroke of the valve and whose inner ends are always covered by said 5 end pistons; the stem passage of one end piston registering with one channel while the passage means of said piston is out of register with the other channel and the stem passage of the other end piston being then out of register with 10 one of the corresponding channels while the passage means of said other piston then registers with the other corresponding channel.

4. A structure as in claim 1 in which said last named means comprises an axial extension projecting from and operatively connected to one end of the valve, a spiral element of relatively great pitch fixed thereon, a member mounted for non-rotary movement axially of the extension and having a slot to fit and engaging the spiral ele- 15

ment, and operating means between the cylinder piston and said member to move the latter and thus rotate the element and extension upon movement of the cylinder piston to adjacent either end of its stroke. 5

5. A structure as in claim 1 in which said last named means comprises an axial non-circular extension rigid with and projecting from one end of the valve, a sleeve turnably mounted in a fixed position against axial movement having 10 a socket in which said extension slidably and non-turnably fits, a stem depending from said sleeve clear of the valve chamber, opposed spiral flanges of relatively great pitch projecting from said stem, a plate bored and slotted fitting over 15 said stem and flanges, means mounting said plate for non-rotary movement in a direction axially of the stem, and operating means between the cylinder piston and said plate to move the latter a predetermined distance and thus rotate the 20 last named stem and valve connected thereto upon movement of the cylinder piston to adjacent either end of its stroke.

AUGUSTUS M. SANBORN.
